DEEP WELL PUMP

Hubert D. Collins, Tulsa, Okla.

Application February 14, 1938, Serial No. 190,482

7 Claims. (Cl. 103—221)

The present invention relates to improvements in pumps, particularly those designed for use in sub-surface oil and water wells, and has for its primary purpose the prevention of what are known in oil field parlance as gas-lock and fluid-pound conditions.

It is well known that in the conventional constructions of these pumps, the plunger on its up-stroke sucks in liquid until such liquid is depleted and then gas is drawn into the chamber above the standing valve. This gas expands as the traveling valve continues its upstroke and when the traveling valve or plunger drops its valve does not open until the gas drawn in as above stated is compressed to the same static pressure as the fluid above the traveling valve.

If the compression-pressure of the fluids below the plunger happens to be less than that of the static pressure above the plunger, its valve will fail to open and a gas-lock condition of the valves results, preventing the transfer of fluid through the traveling valve with each stroke of the pump. This is a common source of trouble in oil field deep pumping resulting in premature failure of the pump plungers due to lack of lubrication by the pumped fluid.

Another prevalent trouble in deep well pumping is fluid-pounding caused by the lack of sufficient fluid in the well to fill the space below the traveling valve or plunger in the working barrel on the up-stroke. When this space is not completely filled on the up-stroke, the plunger falls back in the partially filled space, striking the liquid before the valve in the plunger can open and causing the rods to buckle, thus throwing an extremely heavy load on the tubing with each down-stroke of the plunger. While this difficulty can be remedied to a certain degree by changing the speed and stroke of the plunger, in most cases close adjustments for this purpose cannot be made.

One of the objects of this invention is the elimination of the necessity for proper spacing between the plunger valves to prevent this fluid-pound, by the provision of means for by-passing the liquid above the plunger to the unfilled space below the same at the proper time—that is, at the extreme upstroke. While a portion of the plunger stroke may be sacrificed by the employment of this by-pass arrangement, this is of small consequence compared to the saving that results from smoother rod and tubing operations in plunger wear and breakage of valves.

A further object of my invention is the provision of a valve-controlled by-pass so arranged

in relation to the travel of the plunger that said plunger will displace and open the by-pass valve to permit by-passing of the upper fluids to the space below the plunger to break the gas-lock condition and prevent fluid-pound.

Other and further objects and advantages of the invention will be hereinafter set forth and the novel features thereof defined by the appended claims.

In the drawings:

Figs. 1 and 2 are vertical sectional views of a portion of a pump embodying my invention and showing the traveling valve or plunger at the bottom and top, respectively, of its suction stroke;

Figs. 3 and 4 are similar views of a modification of the invention; and

Fig. 5 is a vertical sectional view of a further modification of my invention.

Like reference characters designate corresponding parts in the several figures of the drawings.

Referring to the drawings, 1 designates the pump tubing leading to the casing packer (not shown) and 2 the working barrel at the base of which is arranged the standing valve 3. The traveling valve 4 is connected to the usual sucker rods by the valve rod 5.

It will be noted that in the present construction the working barrel is provided preferably with a by-pass 6 at opposite sides thereof in the upper entrances of which are located ball valves 7, so arranged that when they are seated to close the by-passes they partially project from the interior wall at the top of the stroke of the traveling valve. Thus when the said valve is raised in the pumping operation to its uppermost position as shown in Fig. 2, the valve contacts with the ball valves to unseat them and open the by-passes so as to establish communication between the upper chamber A and the lower chamber B.

The construction and arrangement above described is a simple and economic one for carrying out the highly important purposes of my invention, but it may be modified, at least as to its valve control, as shown in Figs. 3 and 4. In this latter construction, I substitute a sliding valve 1' for the ball valves 7. The sliding valve is in the form of a sleeve and is so arranged as to normally stand upon a shoulder 8 so as to extend over the upper entrances to the by-passes 6.

The operation of the pump will be clear from the foregoing description, but it may be desirable to note that when gaseous fluids or low fluid wells are being pumped they generally produce a sufficient amount of fluids to fill the space A above

the by-passes, thus creating in the tubing a high pressure before the gas-lock condition as hereinbefore referred to occurs. As the traveling valve reaches its extreme up-stroke position, the by-pass valves are opened and the pressure is released to force the fluids from space A to space B, thus creating the proper condition to break the gas-lock and prevent fluid-pound.

Not only is this difficulty overcome, but the provision of the by-pass creates a condition that will permit greater vacuum to be pulled by the traveling valve through the standing valve, due to the filling of chamber B with fluid. This arrangement is much preferable to that in which the traveling valve passes the ports or openings in the conventional pumps. The accumulation of sand and scale around the traveling valve is prevented and the openings through the pump tube wall can be bored at the proper distance to suit the individual requirements of the pump and pumping conditions.

Referring to Figure 5, the by-pass entrance is located above the working barrel and instead of the pump plunger operating the by-pass valves directly, a special camming sleeve coupling is interposed in the sucker rod for this purpose.

The reference numeral 8 indicates a working barrel to the lower end of which is threaded a lower by-pass coupling 9. A tubing anchor 10 is threaded into the lower end of the coupling and carries the usual standing valve 11. By-pass passages 12, 12 communicate with the interior of the tubing just below the working barrel and extend upwardly, as shown in the drawings, to any suitable location in the pump tubing 13, at which point the upper by-pass coupling 14 is interposed. This coupling is provided with by-pass ball valves 15 for normally closing the by-pass passages 12.

A by-pass valve operating camming sleeve 16 is interposed in the sucker rod string 17 at the proper location so that, as the pump plunger 18 reaches the limit of its pumping stroke, the camming sleeve 16 moves the ball valves 15 off of their seats, permitting the fluid being pumped, due to its static head in the well tubing above the plunger, to enter the by-pass passages 12 and move downwardly into the tubing below the working barrel. This flow of fluid will displace any gas accumulation in the working barrel through the pump plunger valve 19.

While I have shown separate tubular by-pass conduits 12 extending between the upper by-pass coupling 14 and the lower by-pass coupling 9, it should be understood that a single concentric tubular sleeve could be used surrounding the working barrel and that portion of the well tubing below the upper by-pass coupling 14 and suitably secured to the upper and lower by-pass couplings.

Having thus described my invention, what I claim as new and desire to secure by Letters Patent is:

1. In deep well pumps of the class described, a working barrel, a standing valve below the same, a traveling valve operable in said working barrel,

said barrel being formed with an exterior by-pass passage having spaced upper and lower entrance ports opening into the interior of the barrel, its upper entrance to the barrel being above the limit of the upstroke of the traveling valve and its lower entrance to the barrel below the extreme up stroke, so as to equalize the pressures in the tubing above the working barrel and the space below said valve and by-pass the fluids around said valve during the pumping operation, whereby to prevent gas-lock and fluid-pound conditions, and valve means controlling the by-pass passage operable by said traveling valve.

2. A pump as set forth in claim 1, wherein the by-pass valve means is arranged in the path of movement of the traveling valve to be actuated thereby.

3. A pump as set forth in claim 1, wherein the by-pass is provided with a ball valve arranged to be actuated by the traveling valve as it reaches its extreme up-stroke position.

4. A pump as set forth in claim 1, wherein a sleeve valve is slidably arranged in the working barrel normally over the upper by-pass opening, said valve being shiftable by the traveling valve at the extreme up-stroke thereof to establish communication between the pump tubing above the barrel and the space below the traveling valve.

5. A pump as set forth in claim 1, combined with valve means for said by-pass arranged in the path of movement of the traveling valve in the barrel and normally closing the by-pass, said valve means being operable by said traveling valve as it reaches the extreme up-stroke position, whereby to by-pass the fluids above the working barrel into the barrel below the traveling valve.

6. In a deep well pump of the class described, a working barrel, a standing valve below the same, a traveling valve operable in said working barrel, a pump tubing connected with said working barrel, valved by-pass means in the length of said tubing above the working barrel, including a by-pass conduit extending downwardly and connecting with the interior of the pump below the working barrel, a sucker rod for operating said traveling valve, and by-pass valve actuating means on said sucker rod for actuating said valved by-pass means during the operation of said traveling valve.

7. In a deep well pump of the class described, a working barrel, a standing valve below the same, a traveling valve operable in said working barrel, a pump tubing connected with said working barrel, valved by-pass means in the length of said tubing above the working barrel, including a by-pass conduit extending downwardly and connecting with the interior of the pump below the working barrel, a sucker rod for operating said traveling valve, and by-pass valve actuating means on said sucker rod for actuating said valved by-pass means at the termination of the stroke of the traveling valve.
